LOGAN TOWNSEND, OF BOLCKOW, MISSOURI.

STAMP-VENDING MACHINE.

1,196,905.

Specification of Letters Patent. Patented Sept. 5, 1916.

Application filed September 28, 1915. Serial No. 52,981.

To all whom it may concern:

Be it known that I, LOGAN TOWNSEND, a citizen of the United States, residing at Bolckow, in the county of Andrew, State of Missouri, have invented a new and useful Stamp-Vending Machine; and I do hereby declare the following to be a full, clear, and exact description of the invention, such as will enable others skilled in the art to which it appertains to make and use the same.

The present invention relates to a coin actuated vending machine for use in selling postage stamps, and has for its object to provide a vending machine of this character which embodies novel features of construction whereby postage stamps can be handled in roll form and one stamp unrolled and severed at each actuation of the machine.

Further objects of the invention are to provide a stamp vending machine which is comparatively simple and inexpensive in its operation, which can be easily manipulated, which will eject but a single stamp at each actuation thereof, and which can not be operated until after a coin has been properly inserted into the same.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a vertical longitudinal sectional view through a stamp vending machine constructed in accordance with the invention. Fig. 2 is a transverse sectional view taken on the line 2—2 of Fig. 1. Fig. 3 is a transverse sectional view taken on the line 3—3 of Fig. 1. Fig. 4 is a transverse sectional view taken on the line 4—4 of Fig. 1. Fig. 5 is a bottom plan view of the stamp strip cutting mechanism.

Corresponding and like parts are referred to in the following description and indicated in all the views of the drawing by the same reference characters.

Referring to the drawings, which serve to illustrate one embodiment of the invention, the numeral 1 designates a casing which may be mounted in any suitable manner, being provided at the bottom thereof with a pocket or recess 2 into which the hand can

be inserted to withdraw the stamp after the actuation of the machine. Projecting into the casing 1 from the back thereof is a pair of corresponding brackets 3 and 4, said brackets being provided with bearings within which the respective shafts 5 and 6 are journaled. These shafts 5 and 6 are transversely disposed and arranged in alinement with each other, the outer shaft 5 projecting through an opening 7 in the side of the casing 1 and having an operating crank handle 8 applied thereto. The adjacent ends of the shafts 5 and 6 are provided respectively with a coin wheel 9 and an operating wheel 10, said wheels being of substantially the same size and being arranged side by side, so that by locking the wheels together the shafts 5 and 6 can be caused to rotate in unison.

The coin wheel 9 is formed with a deep peripheral groove 11 and also with a radially disposed transverse coin receiving groove 12 intersecting the peripheral groove 11 and extending through the side of the wheel adjacent the operating wheel 10 so as to be susceptible of registering with a similar coin receiving groove 13 in the operating wheel 10. When the grooves 12 and 13 are brought into registry with each other and a coin 14 inserted into the same, the said coin will act as a key to lock the wheels 9 and 10 together. A coin ejecting wire 15 extends through the peripheral groove 11 of the coin wheel 9 at the front of the wheel, the upper end of the wire being secured at 16 to the back of the casing 1, while the lower end of the wire is secured to an arm 17 projecting from the back of the casing. The lower end of the wire 15 is inclined downwardly and rearwardly so as to have an easy inclination which will tend to gradually force the coin 14 downwardly and out of the coin receiving slot 12 when the coin wheel 9 is rotated through the medium of the operating crank 8 to bring the coin to the bottom of the wheel. The coin is thus positively ejected from the slot of the coin wheel 9 when the said coin wheel has been rotated a sufficient amount to unwind a single stamp from the stamp roll. The coin ejecting wire 15 may also be caused to frictionally engage the base of the groove 11 of the operating wheel so as to hold the wheel against accidental rotation. When the coin 14 is ejected by the wire 15 from the coin slot 12, it is directed by a suitable chute 18 into a coin collecting

pocket 19. At the top of the casing 1 a coin slot 22 is provided for the insertion of a coin into the machine, a chute 23 serving to direct the coin from the slot 22 into the coin receiving slot 12 of the coin wheel 9.

A suitable spring 24 is provided for returning the coin wheel 9 to original position after each actuation of the machine. In order to prevent the coin wheel 9 from being rotated backward and thereby causing the mechanism to operate backward as well as ejecting the coin from the coin slot 12 without furnishing a stamp, the coin wheel 9 is provided at its periphery with a ratchet 45 which is engaged by a pawl 46 pivoted upon a bracket 47 secured to the arm 17 projecting from the back of the casing. A plunger rod 48 is pivotally connected to the pawl and is slidably mounted in a standard 49 which projects upwardly from the arm 17 between the wheels 9 and 10, the said plunger rod being provided at its outer end with a head or knob 50. A spring 51 is interposed between the knob 50 and the standard 49, said spring normally holding the pawl in engagement with the ratchet on wheel 9, although when pressure is exerted upon the knob 50 the pawl is disengaged from the ratchet. It will be obvious that the wheel 9 may rotate forwardly, the ratchet teeth sliding under the pawl, but backward rotation of the wheel 9 is prevented. It is necessary, however, to disengage the pawl from the ratchet, so as to allow the wheel to return to its original position after having been rotated to eject a stamp. For this purpose the wheel 9 is shown as provided on the inner side thereof near its periphery with a lug 52 which upon the forward rotation of the wheel 9 strikes the knob 50 on the plunger rod 48 so as to disengage the pawl 46 from the ratchet to allow the wheel to return to its original position after the coin has been ejected. The forward end of the pawl is provided with a rigid extension or arm 53, which when the pawl is disengaged from the ratchet, swings upwardly and rests upon the end of a detent 54 pivoted to the standard 49, as indicated by dotted lines upon Fig. 2. This detent 54 is connected by means of a link 55 to a plunger rod 56 which is slidably mounted upon the standard 49 and extends rearwardly therefrom, the said plunger being provided with a knob 57 upon its outer end. A spring 58 is interposed between the knob 57 and the standard 49 and normally tends to force the detent 54 into the position shown by dotted lines on Fig. 2, although this action is normally prevented by the end of the extension 53 upon the pawl 46. As soon as the wheel 9 returns to its original position the knob 57 on plunger rod 56 is struck by a second lug 59 upon the coin wheel 9 thereby withdrawing

the detent 53 from beneath the extension upon pawl 46, which allows the pawl to again swing into engagement with the ratchet and prevent backward rotation of the wheel 9.

The operating wheel 10 is loose upon the inner transverse shaft 6, although it has a pawl and ratchet connection 26 therewith so that the shaft 6 is rotated upon the forward movement of the operating wheel 10, although the said operating wheel can return to its original position independently of the shaft 6. A suitable spring 27 is applied to the operating wheel for returning it to normal position with the coin slot 13 thereof under the coin tube 23, after each actuation of the machine. With this construction it will be apparent that when a coin 14 is dropped through the slot 22 in the top of the casing, the coin will be directed by the chute 23 into the registering coin receiving slots 12 and 13 of the coin wheel 9 and operating wheel 10 respectively, thereby locking the two wheels together. The operating crank 8 is then rotated until the coin is forcibly ejected from the slots by the wire 15, and the interlocking connection between the two wheels broken. Upon this forward rotation of the coin wheel 9 the operating wheel 10 and shaft 6 will also be rotated, although as soon as the coin is ejected the operating wheel 10 will be returned to normal position by the spring 27 and the interlocking connection between the two wheels broken so that any amount of rotation of the coin wheel 9 in a forward direction will not result in any movement of the operating wheel, and backward rotation of the wheel 9 is prevented by the pawl 46. A person may continue to manipulate the operating crank 8 in a forward direction, although no more stamps will be ejected until another coin is placed in the machine. As soon as the operating crank 8 is released, the spring 24 will return the coin wheel 9 to its original position.

Keyed upon the inner end of the shaft 6 is a pinion 28 which meshes with a gear wheel 29 upon a shaft 30 which is journaled upon a forked bracket 31 and has a feed roll 32 rigidly applied thereto. A co-operating feed roll 33 is applied to a shaft 34 which is parallel to the shaft 30 and is also journaled upon the forked bracket 31. The strip 35 of stamps passes between the two feed rolls 32 and 33 as it is unwound from the stamp roll 36 which is applied to a shaft 37 carried by a pair of brackets 38 projecting from the back of the casing at the top thereof. The relation between the pinion 28 and gear wheel 29 is such that upon each actuation of the coin wheel 9 and operating wheel 10, the feed rolls 32 and 33 will be rotated just a sufficient amount to unwind one stamp from the stamp roll 36.

The stamp strip 35 extends downwardly from the feed rolls 32 and 33, the lower end thereof being carried between a fixed blade 39 and a movable cutting blade 40. An upright guide strip 41 extends between the feed rolls and the fixed blade 39 so as to direct the stamp strip 35 in its movements and cause the lower end thereof to be properly projected downwardly below the fixed blade 39 when the coin control mechanism is operated. The cutting blade 40 is shown as carried by a pair of swinging arms 42 which are pivotally mounted upon a fixed blade 39, and one end of the cutting blade 15 is formed with a handle 43 which extends through an opening 44 in one side of the casing 1. By pushing inwardly upon this handle 43 the cutting blade 40 is moved into engagement with the fixed blade 39 so as to sever that portion of the stamp strip 35 which was projecting below the fixed blade, the severed end of the stamp strip dropping into the before mentioned pocket 2 at the bottom of the casing, from which it can be withdrawn by the hand. As previously explained, the gearing 28 and 29 is so proportioned that a length of the stamp strip 35 corresponding to the length of a single stamp will be unwound from the stamp roll 36 each time the machine is actuated, thereby causing a single stamp to be severed by the knife 40 and removed from the recess 2 each time a coin is inserted in the machine and the operating crank handle 8 manipulated.

Having thus described the invention, what I claim as new and desire to secure by Letters Patent, is:—

1. A device of the character described including a casing, an outer shaft journaled within the casing, an inner shaft journaled within the casing and arranged in alinement with the outer shaft, an operating handle

upon the outer shaft, a coin wheel applied to the outer shaft, an operating wheel upon the inner shaft, said wheels having an opposed relation to each other and being provided with corresponding coin receiving slots, so that a coin within the slots will lock the two wheels together, one of said wheels being also provided with a peripheral groove intersecting the said coin slot, and coin ejecting means arranged within said peripheral groove, so as to eject the coin from the coin slots after the wheels have been rotated a predetermined distance.

2. A device of the character described including a casing, an outer shaft journaled within the casing, an inner shaft journaled within the casing and arranged in alinement with the outer shaft, an operating handle upon the outer shaft, a coin wheel applied to the outer shaft and provided at the periphery thereof with ratchet teeth, an operating wheel applied to the inner shaft, said wheels having an opposed relation to each other and being provided with corresponding coin receiving slots, so that a coin within the slots will lock the wheels together, means for normally preventing rotation of the coin wheel in a backward direction, said means consisting of a pawl engaging the ratchet teeth upon the coin wheel, and means for temporarily disengaging the said pawl from the coin wheel when the same has been rotated a predetermined distance in a forward direction, so as to allow the coin wheel to rotate backward to its original position.

In testimony whereof I have signed my name to this specification in the presence of two subscribing witnesses.
